SAILBOAT HULL WITH RETRACTABLE KEEL

Charles William Lapworth, P.O. Box 1756,
Newport Beach, Calif. 92663

Filed Dec. 5, 1969, Ser. No. 20,388

Term of patent 14 years

Int. Cl. D12—06

U.S. Cl. D71—1

FIG. 1.

FIG. 2.

FIG. 3.

FIG. 1 is a perspective view of a sailboat hull with retractable keel showing my new design;

FIG. 2 is a front elevational view of said sailboat hull;

FIG. 3 is a rear elevational view of said sailboat hull;

FIG. 4 is a side elevational view of said sailboat hull, the side opposite that shown in FIG. 4 being identical to the side shown in FIG. 4;

FIG. 5 is a top plan view of said sailboat hull; and

FIG. 6 is a bottom view of said sailboat hull.

I claim:

The ornamental design for a sailboat hull with retractable keel, substantially as shown and described.
